US00D902709S

(12) **United States Design Patent** (10) **Patent No.:** **US D902,709 S**
De Pietri Tonelli et al. (45) **Date of Patent:** **** Nov. 24, 2020**

(54) **PACKAGE FOR FOODSTUFF**

(71) Applicant: **TETRA LAVAL HOLDINGS & FINANCE S.A.**, Pully (CH)

(72) Inventors: **Roberto De Pietri Tonelli**, Colombaro di Formigine (IT); **Luisa D'Amato**, Modena (IT); **Marcello Barbieri**, Modena (IT); **Marco Marchetti**, Carpi (IT); **Alberto Mameli**, Modena (IT); **Davide Morciano**, Modena (IT)

(73) Assignee: **TETRA LAVAL HOLDINGS & FINANCE S.A. (CH)**

(**) Term: **15 Years**

(21) Appl. No.: **35/506,763**

(22) Filed: **Oct. 19, 2018**

(80) **Hague Agreement Data**

Int. Filing Date: **Oct. 19, 2018**

Int. Reg. No.: **DM/200852**

Int. Reg. Date: **Oct. 19, 2018**

Int. Reg. Pub. Date: **May 17, 2019**

(30) **Foreign Application Priority Data**

Apr. 20, 2018 (EM) 005241767

(51) **LOC (12) Cl.** **09-01**

(52) **U.S. Cl.**
